UNITED STATES PATENT OFFICE.

HARRY ETHERIDGE, OF ZELIENOPLE BOROUGH, PENNSYLVANIA.

RAILWAY-TRACK CONSTRUCTION.

Application filed August 10, 1927. Serial No. 211,902.

More particularly, my present invention relates to railway track construction which includes the use of individual rail supports which do not span the space between the 5 parallel rails of the track nor support both of the parallel rails thereof, as do the cross-ties now in common use.

It is recognized in the railway track art that many important advantages attend the 10 substitution of individual rail supports for the conventional cross tie, such, for instance, as the provision of more extended supports for the rails to protect them from bending stresses.

15 However, the tendency of the rail to tip and roll both inwardly and outwardly appears in the use of the individual rail supports, as it does also when cross-ties are used, and should be counteracted.

20 For this purpose I have invented the cruciform rail supports which form the subject matter of my application for Letters Patent filed in the United States Patent Office on November 11, 1926, Serial 25 Number 147,634.

In the use of these supports in actual service I have discovered a tendency toward an outward shifting of the supports relative to the axis of the tracks which exerts 30 tension strains on the tie-rods which are usually provided to hold the rails in parallelism.

I have therefore made a further improvement in my cruciform rail supports which 35 prevents such outward shifting and causes the strains which tend to cause the same to be assumed by the ballast or road bed.

I prefer to provide my cruciform rail support with a larger bearing area on the 40 inside of the rail as the rolling or tipping forces which are exerted toward the axis of the track are greater than those exerted in the opposite direction.

I also provide an improved metallic reinforcement which is embedded in the concrete or other material of which I form my rail support.

Other novel features of construction, and 50 also of arrangement of parts, will appear from the following description.

In the accompanying drawings, wherein I have illustrated the best embodiment of the principles of my invention now known to me, Fig. 1 is a plan view showing my 55 improved rail supports in use to support the parallel rails of a track; Fig. 2 is an en-

larged plan view of one of said supports, the two part mat being partially broken away for the sake of better illustration; Fig. 3 is a side elevation of the support 60 looking from the axis of the track; Fig. 4 is an end view of the support, and Fig. 5 shows in enlarged perspective the metal skeleton which is embedded in material of the support to reinforce the latter. 65

Referring to the drawings, 1 and 1^a represent the parallel rails of the track, each supported from beneath by the individual rail supports 2, said opposite supports being unconnected with each other and being 70 embedded in the ballast.

The supports 2 are substantially cruciform, the longitudinal leg or beam 3 being the rail supporting member extending longitudinally of the rail to provide an extended support for the latter. 75

The two transversely disposed legs 4 and 5 which extend inwardly toward the axis of the track and outwardly in the opposite direction, respectively, as shown in Fig. 1, 80 are the outer and inner stabilizing legs. The inner stabilizing leg 4 is preferably given a larger bearing area on the ballast or road bed as the tendency toward inward rolling of the rail is the greater. 85

To counteract the tendency, already referred to, of the rail support to be thrust outwardly away from the axis of the track, I form the inner stabilizing leg 4 of such shape that it will bind in the ballast and resist such outward thrusts. 90

Thus, as a preferred embodiment I cause the side walls or surfaces of the leg 4 to diverge toward the axis of the track, making the said leg of what may be termed "fish-tail" shape so that it will be wedged in the ballast and will thus anchor the rail support against outward movement. 95

The leg 4 has preferably about one and one-half the bearing area on the road bed 100 that the leg 5 has.

The top surfaces of the legs 4 and 5 are preferably at a lower level than that of the longitudinal beam 3 and the top edges of the support are preferably beveled, as shown. 105 Thus the support may be more easily nested in and more securely anchored to the ballast.

The rail does not rest directly on the beam 3 as the result would be the direct transference of the jars and thrusts of traffic from 110 the rail to the body of the support.

To prevent this, I provide the upper sur-

face of the beam 3 with a sunken seat 6 of slightly greater width than the base of the rail and extending along said beam to near each end thereof. In said seat I mount a cushion means which directly supports the rail. Said cushion means preferably comprises an under mat 7 which lies in the bottom of the seat 6 and an upper mat 8 which rests on the mat 7 and protrudes upwardly out of the seat. The mats are both preferably made of resilient material, such as rubber, asphalt composition and the like, or a combination thereof, the under mat being the more elastic than the upper mat. The combined thickness of the mats is sufficient to prevent the rail being depressed into direct contact with the beam 3.

Any convenient means may be employed to fasten the rail to the support. I prefer to employ rail fastening means of the character described and shown in Letters Patent of the United States No. 1,586,617, issued to me June 1, 1926, and in the drawings I show the screw sockets 9 which are anchored and embedded in the material of the rail support at either side of the seat 6 and adjacent either end of said seat, the fastener bolts being screwed down into said sockets as will more clearly appear from said Letters Patent.

The metallic reinforcement which I preferably employ to reinforce the concrete from which I preferably form my improved rail support is shown unembedded in Fig. 5, and is of the following character.

10 represents a set of four parallel top bars and 11 a like set of four parallel bottom bars, each of the bottom bars being parallel with the corresponding top bar. The members of the top set of bars 10 are connected together at their ends by the cross-bars 12 which contact with the under side of the bars 10 and are welded or otherwise secured thereto. The ends of the lower bars 11 are connected to the cross-bars 12 by the vertical posts 13 which are welded or otherwise secured at their ends.

14 represents a pair of upper parallel bars which are disposed at substantially right angles to the bars 10 and cross beneath and in contact with the same and are welded or otherwise secured thereto. 15 represents a similar pair of lower parallel bars also parallel with the bars 14 and which cross over and are in contact with the bars 11 and are welded or otherwise secured to the latter. The ends of the bars 14 are connected by the cross bars 16 which contact with the undersides of the bars 14 and are welded or otherwise secured thereto. Also the ends of the bars 15 are connected by the cross bars 17 which contact with the lower surfaces of the latter and are welded or otherwise secured thereto. The bars 14 at the inner side of the support have also an extra connecting

cross-bar 18, and the bars 15 an extra cross bar 19 to further brace the inner stabilizing leg of the rail support. Posts 20 have their lower ends stepped on the bars 15 and their upper ends abutting against the under surfaces of the cross-bars 16, the ends of the posts being welded or otherwise secured in place.

Additional posts 21 are interposed between the intermediate cross-bar 18 and the bars 15 with their ends welded or otherwise secured in place.

Also posts 22 are interposed between the bars 14 and 15 where they intersect with the bars 10 and 11, respectively.

The two central bars 10 are so positioned as to extend longitudinally of the beam 3 beneath the seat 6 and adjacent to each lateral edge of the same, and are located close to the floor of said seat to directly assume the thrusts and jolts incident to traffic on the rails, a relatively thin covering of concrete being provided, sufficient to protect the metal from oxidizing. Thus the metal reinforcement effectually relieves the concrete and prevents its rupture, crushing or fracture.

The outer bars 10 and 11 are positioned adjacent to the bases of the stabilizing legs 4 and 5, and thus prevent fracture or cracking longitudinally of the rail supporting beam 3.

The sockets 9 are positioned in the corners formed by the two inner bars 10 and their cross bars 12 and are welded or otherwise secured to said bars and to the posts 13 before the skeleton is embedded in the concrete. Thus the strains exerted on the rail fastening devices are transferred directly to and assumed by the reinforcement, thereby further protecting the concrete from injury.

What I desire to claim is:—

1. In a railway track structure, the combination with the parallel rails, of individual supports for the opposite rails of substantially cruciform shape and each comprising a beam extending longitudinally under the rail for the support thereof and two stabilizing legs extending at substantially right angles to the beam, the inner stabilizing leg being shaped to become wedged in the ballast to resist movement outwardly of the track.

2. In a railway track structure, the combination with the parallel rails, of individual supports for the opposite rails of substantially cruciform shape and each comprising a beam extending longitudinally under the rail for the support thereof and two stabilizing legs extending at substantially right angles to the beam, the inner stabilizing leg having a laterally enlarged free end so as to be wedged in the ballast against movement outwardly of the track.

3. In a railway track structure, the combination with the parallel rails, of individual

supports for the opposite rails of substantially cruciform shape and each comprising a beam extending longitudinally under the rail for the support thereof and two stabilizing legs extending at substantially right angles to the beam, the inner stabilizing leg having its lateral edges diverging toward its free end to wedge the leg in the ballast against movement outwardly of the track.

10 4. In combination with an individual rail support of concrete and of cruciform shape having a rail-supporting beam extending longitudinally beneath the rail and stabilizing legs extending in opposite directions and substantially at right angles to the beam, of an embedded reinforcement for said support of cruciform shape and formed of metal bars, the reinforcement for the beam comprising two sets of four parallel bars, one

15 set being disposed above the other and the corresponding bars of each set being connected by vertical posts, and cross-bars connecting ends of the bars of a set, and two sets of parallel bars spaced apart vertically disposed transversely of the first mentioned sets and intersecting the same, the corresponding bars of the second named sets being connected by vertical posts and the ends of the bars of the second named sets being connected by

20

25

cross-bars, the bars being connected together 30 at their meeting points.

5. In combination with an individual rail support of concrete and of cruciform shape having a rail-supporting beam extending longitudinally beneath the rail and stabilizing legs extending in opposite directions and substantially at right angles to the beam, of an embedded reinforcement for said support of cruciform shape and formed of metal bars, the reinforcement for the beam comprising two sets of four parallel bars, one 40 set being disposed above the other and the corresponding bars of each set being connected by vertical posts, and cross-bars connecting ends of the bars of a set, two sets 45 of parallel bars spaced apart vertically disposed transversely of the first mentioned sets and intersecting the same, the corresponding bars of the second named sets being connected by vertical posts and the ends of the 50 bars of the second named sets being connected by cross-bars, the bars being connected together at their meeting points, and vertical supporting posts at the intersections of the sets.

Signed at Pittsburgh, Pa. this 8th day of August, 1927.

HARRY ETHERIDGE.
